CLAIM

The ornamental design for a vacuum bottle, as shown
and described.

DESCRIPTION

FIG. 1 is a perspective view of a vacuum bottle showing
my new design, the vacuum bottle being symmetrical
about a longitudinal center line;

FIG. 2 is a side elevational view thereof, the other sides
being mirror images thereof;

FIG. 3 is a top plan view thereof; and

FIG. 4 is a bottom plan view thereof.

FIG. 1

FIG. 2

FIG. 3

FIG. 4
